UNITED STATES PATENT OFFICE.

ALFRED H. HUMPHREY, OF NEW YORK, N. Y., ASSIGNOR TO GENERAL GAS LIGHT COMPANY, OF KALAMAZOO, MICHIGAN.

PROCESS OF MAKING FIREBACKS FOR GAS-STOVES.

1,396,209.

Specification of Letters Patent. Patented Nov. 8, 1921.

Application filed May 3, 1920. Serial No. 378,587.

To all whom it may concern:

Be it known that I, ALFRED H. HUMPHREY, a citizen of the United States, residing at the city and county of New York, State 5 of New York, have invented certain new and useful Improvements in Processes of Making Firebacks for Gas-Stoves, of which the following is a specification.

This invention relates to improvements in 10 the process of making firebacks for gas stoves.

My improved process is especially desirable for making firebacks for gas stoves such as shown in my application for patent filed 15 concurrently herewith.

The main objects of this invention are:

First, to provide an improved process of manufacturing firebacks with raised flange-like portions partially colored.

Second, to provide an improved process of manufacturing firebacks having border portions thereof colored to produce an ornamental effect.

Further objects and objects relating to 25 structural details will definitely appear from the detailed description to follow.

I accomplish the objects of my invention by the device and means described in the following specification. The invention is 30 clearly defined and pointed out in the claims.

A structure which is a preferred embodiment of my invention is clearly illustrated in the accompanying drawing forming a part of this specification, in which:

Fig. I is a front elevation of a fireback produced by my novel process.

Fig. II is a perspective view of a laminated pile of plastic composition illustrating one step of the production of the color 40 sheets or strips.

Fig. III is a front elevation showing another step of the process, namely, the forming of the body portion prior to the incorporation therewith of the colored material.

Fig. IV is a front or plan view of the body portion of the fireback with the sheets or strips of the colored composition disposed thereon.

Fig. V is an enlarged vertical section on a line corresponding to line 5—5 of Fig. IV, showing the mold or form in retracted position.

Fig. VI is a sectional view of the parts shown in Fig. V, with the mold or form 55 actuated.

Fig. VII is an enlarged detail view of the fireback.

In the drawing similar reference characters refer to similar parts throughout the several views.

In carrying out my improved process, I first mold or form the body portion 1—see Figs. III, V and VI—from a suitable plastic clay composition preferably having fine granular material such as saw dust incorporated therein, the granular material being destroyed during the firing so that the fireback has a more or less porous character and I find is not likely to warp or crack under repeated heating and cooling and uneven heating such as occurs in use in the gas stove.

The fireback shown is provided with raised flange-like border portions 2 at the top and ends. After forming this body 75 portion 1 of the uncolored plastic clay composition, I superimpose sheets 3 of plastic clay composition preferably the same as that of which the body portion is formed, upon the raised portion 2 of the body as shown 80 in Figs. IV and V, and press the superimposed sheets or strips upon the plastic molded body by means of the mold 4 as shown in Figs. V and VI, so that the sheets become an integral part of the body.

The sheets have portions 5 thereof indicated conventionally in Fig. IV, colored with an oxid coloring material which does not run when heated and becomes fixed by firing. The strips 3 are preferably formed 90 by stacking alternate layers 6 and 7 of the colored and uncolored plastic material in a pile as shown in Fig. II, and pressing together into a substantially composite or integral mass and then slicing off the strips 3 95 as indicated by the dotted lines in Fig. II. This, I find, is a very practical method although narrow strips or pieces of the colored composition may be laid separately upon the body while it is still in its plastic condition 100 and pressed into the same.

The pressing distributes the colored clay more or less unevenly so that a natural effect or appearance is secured.

Firebacks made by my process are very 105 attractive in appearance. The firebacks also have the further advantage of not showing discoloration from the gases or products of combustion.

I have illustrated one method of carrying 110

out my improved process which I find very practical in use, but this may be considerably modified according to the product desired.

5 Having thus described my invention, what I claim as new and desire to secure by Letters Patent, is:

1. The process of making gas stove fire-backs having a raised or flange-like portion, 10 comprising molding the fireback of a plastic clay composition, superimposing on the said raised portion a plastic sheet of the same clay composition having alternate transverse strips of portions thereof colored with 15 an oxid coloring material, the clay composition having a fine granular material adapted to be destroyed by the subsequent firing step pressing the superimposed sheet upon the plastic molded body so that the sheet becomes an integral part thereof, and firing.

2. The process of making gas stove fire-backs, comprising molding the firebacks of a plastic clay composition, superimposing thereon a plastic sheet of the same clay composition having portions thereof colored, the 25

clay composition having a fine granular material adapted to be destroyed by the subsequent firing step pressing the superimposed sheet upon the plastic molded body so that the sheet becomes an integral part 30 thereof, and firing.

3. The process of making gas stove fire-backs, comprising molding the firebacks of a plastic clay composition, superimposing plastic clay composition colored with an 35 oxid coloring material, the clay composition having a fine granular material adapted to be destroyed by the subsequent firing step, incorporated therein, pressing the superimposed composition into the plastic molded 4 body so that they become an integral part, and firing.

In witness whereof, I have hereunto set my hand and seal in the presence of two witnesses.

ALFRED H. HUMPHREY. [L.S.]
